Patented Dec. 13, 1921.

Linnæus E. Baker, INVENTOR.
BY *Walter A. Knight*, ATTORNEY

UNITED STATES PATENT OFFICE.

LINNAEUS E. BAKER, OF FORT WAYNE, INDIANA, ASSIGNOR TO WAYNE OIL TANK & PUMP COMPANY, OF FORT WAYNE, INDIANA, A CORPORATION OF INDIANA.

CHECK-VALVE.

1,400,011.

Specification of Letters Patent. Patented Dec. 13, 1921.

Application filed September 18, 1917. Serial No. 191,925.

To all whom it may concern:

Be it known that I, LINNAEUS E. BAKER, a citizen of the United States, residing at Fort Wayne, in the county of Allen and 5 State of Indiana, have invented new and useful Improvements in Check-Valves, of which the following is a specification.

My invention relates to metallic valves and particularly those of the spring closing 10 check valve type used in pump construction, etc., and is especially useful in mechanism intended to deliver accurately gaged quantities of fluid, such for example as gasoline; its object being to improve and simplify 15 construction, secure certainty and precision of action, and at the same time facilitate inspection, renewal, etc., as a guard against impairment of action from accidental causes.

In the particular embodiment of my invention selected for illustration, my improvement is shown adapted for use as a check valve in the bottom cylinder head of a self-measuring pump and in the same device also applied as a piston valve.

25 The figure is a vertical axial section through the pump cylinder, bottom cylinder head, and attendant parts.

Referring now to the drawings: C is a pump cylinder, adapted to receive the reciprocating piston A, composed of the crib a fixed to the piston rod a¹, which extends 30 through into the crib to form a valve guide a². A follower plate a³ is threaded into the crib a and has at the bottom an outwardly 35 extending circumferential flange a⁴, which securely holds the cup-leather B against the bottom of the crib, while the piston ring D expands the cup-leather in the usual manner. The upper end of the follower plate a³, 40 has a suitable axial opening to form the valve seat a⁵.

A valve E adapted to seat on the valve seat a⁵, has an upwardly extending boss e, bored axially to receive and embrace the 45 valve guide a², in a close sliding fit and is provided with a vent e¹ at or near the bottom of the bore. The length of the boss e limits the movement of the valve, and the valve guide is of such length as to permit 50 free movement of the valve within this limit, while the vent discharge tends to regulate and prevent too sudden movements of the valve in relation to its seat.

A slot e² in the bottom of the valve across the center is adapted to receive a tool for 55 rotation of the valve in grinding the valve to its seat. A spring S coiled about the valve boss e seats against the under side of the top of the crib a and the upper side of the valve E, and is normally under compression to 60 exert pressure tending to hold the valve to its seat.

Obviously, unscrewing the follower plate a³ permits the valve E and spring S to be 65 taken out for renewal or repair.

The bottom cylinder head F has a laterally projecting portion f adapted to receive the check valve hereinafter to be described.

The seat f⁵ is the counterpart of the seat a⁵. The valve and spring are in all respects 70 similar to the other valve and spring before described, and all parts are similarly lettered. The valve guide f² is the counterpart of the valve guide a², but is fixed to the cap F¹ which is threaded into the bottom cylinder head F in axial alinement with the valve seat f⁵. This spring S seats against the under side of the cap F¹, and the upper side of 75 the valve E in the same manner and for the same purpose as the spring of the piston 80 valve.

Obviously, unscrewing the cap F¹ permits the valve E and spring S to be taken out for 85 renewal or repair.

I claim as my invention and desire to secure by Letters Patent of the United States:—

In an improved check valve, the combination of a casing provided with a valve seat, a valve adapted to close on said seat, said valve having a hollow stem forming an axially extending socket provided near the base of said socket with a laterally extending vent passing through the side thereof, a guide fixed to the casing and forming a 90 plunger to reciprocate within the hollow stem, and a coiled spring surrounding said hollow stem to hold the valve normally in its closed position.

In testimony whereof I have hereunto set 100 my hand in presence of two subscribing witnesses.

LINNAEUS E. BAKER.
